UNITED STATES PATENT OFFICE

116,209

DESIGN FOR A FILTER BODY

Oscar Freiherr von Kohorn zu Kornegg, New York, N. Y., assignor to Oscar Kohorn & Co., Ltd., New York, New York, N. Y., a corporation of New York

Application December 20, 1938, Serial No. 81,895

Term of patent 14 years

To all whom it may concern:

Be it known that I, Oscar Freiherr von Kohorn zu Kornegg, a citizen of Germany, residing at New York, in the county of New York and State of New York, have invented a new, original, and ornamental Design for a Filter Body, of which the following is a specification, reference being had to the accompanying drawing, forming part thereof.

In the drawing

Fig. 1 is a front elevational view of a filter body showing my new design.

Fig. 2 is a top plan view thereof.

Fig. 3 is a bottom plan view thereof.

I claim:

The ornamental design for a filter body, as shown.

OSCAR FREIHERR VON
KOHORN ZU KORNEGG.
